ABSTRACT

Device for the sterilization of ampoules comprising a rotatable drum, means for maintaining ampoules in position comprising at least one pair of wires maintained under tension on said drum, and sterilizing means for sterilizing ampoules held by said wires.

FIG 5

FIG 6

DEVICE FOR THE STERILIZATION OF AMPOULES

Known devices for the sterilization of ampoules have certain disadvantages.

The majority of these devices comprise a tunnel through which the ampoules are moved. It is necessary for these tunnels to be extremely long and cumbersome since a considerable time is necessary for the drying of the ampoules even more so when these ampoules are held by devices amongst others aluminium plaques, which noticeably prolong the evaporation time and thus the time for drying the washing water.

Rotatable devices have also been produced. These, while being less cumbersome than the tunnels do not give entire satisfaction. Thus ampoules are placed in racks the mass of which considerably slows down the heating and consequently the sterilization.

Consequently the invention proposes to provide a rotatable device for the sterilization of ampoules which allows an automatic loading and unloading of ampoules without racks at the same time considerably reducing the sterilization time, thus assuring an increased output for lower bulkiness than with known devices.

To this end, the invention provides a rotatable device for the sterilization of ampouls characterized in that the drum, associated with loading and unloading means and capable of being provided with safety devices, comprises pairs of stretched wires assuring the maintenance of the ampoules.

The invention will be well understood by referring to the following description made by way of nonlimiting example, as well as to the enclosed drawings in which:

FIG. 1 is a schematic representation of the principle of the device.

FIG. 2 is a partial view of the drum with the wires.

FIG. 3 is a section of the means of fixation and tension of the wires.

FIG. 4 is a view of a loading plate provided with ampoules.

FIG. 5 is a perspective view of the assembly of the loading means.

FIG. 6 is a section of the loading means, and

FIG. 7 is a section of the unloading means.

Referring to FIG. 1, the rotatable sterilization device comprises a drum 1 turning about its axis and provided with loading means 2 and unloading means 3. These means 2 and 3 are preferably automatic but the feeding of means 2 and/or the emptying of means 3 can be manual. The drum is partially enclosed by a stationary enclosure 50 extending angularly from the loading means 2 to the unloading means 3.

During a part of their path, the ampoules 4 are heated by heating organs 5, preferably electric. The cooling down is assured by a current of sterilized air 6. The ampoules 4 thus arrive at the unloading means 3 at the desired temperature.

Referring to FIG. 2, the drum 1 comprises two side plates 7 and 8 between which are stretched pairs of wires parallel to the axis of the drum 1. The two wires 9 of a pair are close enough together to assure fixation of the ampoules 4 at the level of their necks 10. The said ampoules 4 are thus sufficiently maintained in position and no accessory element is interposed to their heating nor to their recooling.

It is preferable that at the moment of the introduction or the removal of ampoules 4, the two wires 9 of a pair are separated one from the other so that the movement of the said ampoules 4 can take place without forcing. Referring to FIG. 3 there is shown an example of an embodiment for tensioning the wires.

The two wires 9 of a pair are formed in fact from one single wire 9' of which the two extremities 11 and 11' are fixed in a stopper 12 of which a part 13 penetrates into side plate 7. On the side of plate 8 the wire 9' is doubled back by an axle 14 solid with an element 15 which can slip in the socket 16 which penetrates in the said side plate 8. A spring 17 supported on the socket 16 tends to repel the element 15 and ensures the tension of the wire 9'. To disengage wire 9' from the drum it is sufficient to press on the element 15 which loosens the wire 9' and allows disengagement of the stopper 12. Slots 7' and 8' provided respectively in the two side plates 7 and 8 thus per-

mit the positioning of the assembly of wire 9'—stopper 12—socket 16.

Referring to FIGS. 4, 5 and 6, the ampoules 4 are lodged in a rack 18 provided with cavities 19 furnished, at the bottom, with hole 20. The said rack 18 slides in inclined guides 21 until it is stopped by the first row of ampoules which comes into engagement against an abutment 22.

Said abutment 22 is provided with steps 23 each cooperating with an ampoule 4 and assuring its guidance in the sense of arrow a. A rake 24, movable in the sense of arrow a by the aid, for example, of a pneumatic jack 25, is provided with rods 26 disposed in a manner such that they can penetrate into the holes 20.

When a pair of wires 9 is in position the drum 1 stops and the rake 24 is moved up. The rods 26 pass through the holes 20 in the upward direction towards ampoules 4 of the row in contact with the abutment 22.

An element 27 furnished with steps 28 similar to steps 23 is positioned in alignment with the abutment 22 and assures the continuity of guidance of the ampoules 4 until their necks 10 are placed between the wires 9. At this moment the movement of rake 24 is interrupted.

While the drum is stopped two punches 29 are moved to separate the wires 9 one from the other. When the ampoules 4 are in position the punches 29 retract and ampoules 4 are maintained in place by the wires 9. At this instant the rake 24 moves back down, the rods 26 are extracted from holes 20 and the rack 18 advances by one row. The element 27 can be movable about an axis 30 in the sense of arrow b to move the ampoules 4 which were not taken up by the wires 9 or which had broken.

Referring to FIG. 7, when the row of ampoules 4 maintained between the wires 9 arrive at the level of the unloading means 3 the drum is stopped. Punches (not shown) similar to the punches 29 move to separate the wires 9 and the ampoules 4 of the row slide in the direction of arrow c until an abutment plate 31. A fixed element 32 furnished with steps and analogical to the element 27 assures guiding of the ampoules 4 during their descent.

An element 33 which elongates element 32 is solid with the abutment plate 31 and serves to maintain in place ampoules 4 which have arrived on said plate 31, which is carried by an arm 34 movable about an axis 35. The plate 31, loaded with the row of ampoules 4 is turned about the axis 35 until it comes into place horizontally behind an evacuating table 36.

At this moment the element 33 slides with respect to the plate 31 in the direction of the arrow d and pushes the ampoules 4 onto the table 36. Then the assembly of plaque 31—element 33 is replaced in its initial position. Any means whatsoever (wires, plates) can be placed to prevent the ampoules 4 falling from the table 36.

Naturally, other means of unloading and loading can be used. It is equally possible to preview various safety means. Thus for example it is appropriate to prevent the supply of ampoules 4 when a wire 9, in the supply position, is broken.

To this end it is sufficient to place at a suitable position an electrical contact actuated by the element 15 which, when the wire 9 is broken, moves out of the socket 16 under the action of spring 17.

Whilst the invention has been described in relation to a particular embodiment, of course it is not limited thereto and various modifications of form and matter can be made without departing from the spirit and the scope of the invention.

65 What is claimed is:

1. Device for the sterilization of ampoules comprising a rotatable drum, drive means for rotating said drum, means for maintaining ampoules in position comprising at least one pair of wires maintained under tension on said drum, an angularly fixed heating enclosure partially enclosing said drum, and electric heating means in said enclosure for heating and thereby sterilizing ampoules held by said wires.

2. Device as claimed in claim 1, wherein said wires are positioned substantially at the edges of the drum and substantially parallel to the axis thereof.

3. Device as claimed in claim 1, wherein each of said pairs of wires comprises a single wire the two ends of which are fixed at one edge of the drum, the wire being maintained under tension by the action of a spring at the axially opposing edge of the drum.

4. Device as claimed in claim 3, wherein the sides of the drum are provided with axially opposite slits provided with stopper members for fixing said wires therein.

5. Device as claimed in claim 4, wherein each axially opposite pair of stopper members comprise one member with a socket containing a spring acting on an axle engaging said wire near its mid-point and tensioning said wire and another member provided with two holes and means for locking the ends of the wire therein.

6. Device as claimed in claim 1, comprising means for loading a plurality of ampoules onto a pair of wires.

7. Device as claimed in claim 6, wherein said loading means comprises a plurality of inclined guides in which ampoules may be slidingly supplied, means for moving said ampoules along said guides, means for separating pairs of wires for engagement of ampoules therein and bringing said pairs of wires together to maintain said ampoules in position.

8. Device as claimed in claim 1, comprising unloading

means for unloading a plurality of ampoules engaged in a pair of wires.

9. Device as claimed in claim 8, comprising means for separating pairs of wires to release ampoules maintained therein, inclined means adapted to receive released ampoules by sliding therein, stop means for said ampoules provided on said inclined means, said stop means and at least part of said inclined means adapted to rotatably transfer said ampoules to a desired position.

10. Device as claimed in claim 1, wherein each of said pairs of wires is provided with signal means which operate if the wire breaks.

11. Device as claimed in claim 1, provided further with means for providing a current of sterilized air on the drum at a fixed angular position for cooling said ampoules after they have been sterilized by said heating means.

12. Device as claimed in claim 1, comprising means for stopping said drum with a pair of wires at said angularly fixed positions for loading and unloading ampoules, and means for initiating rotation of the drum once said operations of loading and unloading are terminated.
